UNITED STATES PATENT OFFICE.

HANS SCHÜTTE, OF RHEINE, GERMANY, ASSIGNOR TO THE FIRM OF RHEINEE MASCHINENFABRIK WINDHOFF AKTIEN-GESELLSCHAFT, OF RHEINE, WESTPHALIA, GERMANY, A CORPORATION OF GERMANY.

TURNTABLE.

Application filed August 29, 1921. Serial No. 496,624.

(GRANTED UNDER THE PROVISIONS OF THE ACT OF MARCH 3, 1921, 41 STAT. L., 1313.)

To all whom it may concern:

Be it known that I, HANS SCHÜTTE, a citizen of the Republic of Germany, and resident of Rheine, Westphalia, Germany, have 5 invented certain new and useful Improvements in Turntables (for which I have obtained patents as follows: Germany, filed Aug. 18, 1915, Patent No. 337,525; Germany, filed Aug. 21, 1915, Patent No. 310,301; Germany, filed Mar. 10, 1916, Patent No. 306,704; Austria, filed Aug. 16, 1918, Patent No. 81,014; Hungary, filed Aug. 17, 1918, Patent No. 74,900; Sweden, filed Aug. 23, 1918, Patent No. 48,983; Belgium, filed Sept. 15 10, 1918, Patent No. 273,754; Czechoslovakia, filed Jan. 16, 1920, Patent No. 3,898), of which the following is a specification.

This application refers to turn-tables and more particularly to such turn-tables, in 20 which the main girders are divided in the middle of their length above the center-bearing, and an important part of the present invention consists in arrangements for the discharging from stress, of the sheets or 25 plates, which connect the halves of the girders and in connecting the middle ends of the main girders unyieldingly to the center-bearing. In the turn-tables with subdivided main-girders, as they are known hitherto, those connecting sheets or plates are subjected to considerable combined 30 stresses both in regard to stretching and in regard to bending strain, which take place in consequence of the changes of the load on the turn-table, and especially in consequence of the partial sinking down of the level of the track of the platform-rollers; and in consequence of those strains an obnoxious 35 lengthening and even a breaking of those sheets or plates are not uncommon happenings.

In order to overcome those drawbacks, according to the invention the laminated sheet or other combining member is arranged at 40 the lower side of the ends of the girders, which face each other; and outside of the theoretical lines of contact between the girder-bearing support on the center-bearing and the girder-ends this sheet turns or 45 bends round the form of the girder-ends, whereas within those lines of contact it turns

or bends round the form of the surface of the aforesaid support.

Another feature of the invention consists in arranging on the turn-table horizontal 55 rollers, which bear against an abutment-ring on the center-bearing, so that each half of the turning platform is left free to follow the up- or down-movements, which may take place at the outer ends of the turn-table; 60 whilst any edgewise-tilting-momentum, which in consequence of onesided load, may take place vertically to the longitudinal axis is transferred, without play, to the center-bearing. By this arrangement such 65 forces or strains, as occur at the one side only, are neutralized, which forces are caused by differences of the load on the same axis, resulting for instance from the pressure of the wind, which bears considerably 70 against turn-tables arranged in the open air, and which pressure of wind is especially dangerous to turn-tables of the here-described kind.

A further feature of the present invention 75 consists therein, that it enables of eight rollers arranged in pairs at the ends of the main girders to drive only one single roller-wheel, whereas hitherto at least two roller-wheels had to be driven. To turn the turn-table 80 even if it is unloaded, by driving one single roller-wheel only a sufficient bearing-pressure on this roller-wheel must be provided for, and to this effect the support holding this roller-wheel is prolonged laterally, and on this prolongation there has been placed the driving mechanism, which is separated 85 from the main construction of the turn-table.

In order to make the invention clearly understood a preferred embodiment of it has been illustrated in the drawings, in which—

Figure 1 is a side-view or elevation of a turn-table according to the invention;

Figure 2 is a top view corresponding to Figure 1;

Figure 3 is a vertical cross-section through the central part of the turn-table showing in particular the lateral supporting 100 or stiffening of the platform;

Figure 4 is a side-view of the parts shown

in Figure 3 with the above mentioned connecting-plate shown in section;

Figure 5 is a plan-view of the parts shown in Figure 3;

5 Figure 6 is a side-view, and Figure 7 is a top-view of the arrangement of the roller-wheels and the parts for driving the latter.

As to the illustrated embodiment of the invention 1 and 2 are the main-girders of 10 the turn-table, which are divided at the middle of their length above the center-bearing 3. The two halves are connected by the laminated plate 4, which is shown in the Figures 1 and 4 to rest or so to say 15 ride on the upper surface of a support 6 which latter is supported by the center-bearing and arranged crosswise to the longitudinal axis of the turn-table and provided with curved or a plane upper surface 20 and with rounded edges. The Figures 3 and 5 show, that the connecting member 4 along the transversal axis of the turn-table by a number of screws, is fixed to the support 6. The two ends of the main-girder- 25 halves 5, which face each other, are provided, in the shown embodiment, with inclined lower flanges, and to the surface of those flanges the flexible connecting-member or plate 4 has been fixed by screws, or the 30 like. This connection however must not extend as far as the innermost ends of the girders, but on the contrary it must cease already in a certain distance from the inner 35 ends of the girders, namely outside the possible theoretical line of contact between the support 6 and the girder-ends. The unfastened zone must be provided for, in order to enable the flexible connecting-member or plate 4 to act like an open roller-bearing.

40 The connecting-member or plate 4 may have any breadth and may consist in a single piece, or it may be as broad as the whole turn-table, or it may be subdivided into several narrower laminae or strips, or 45 it may be arranged one separate sheet or plate below each main-girder, as it is shown in the Figure 3. The connecting-member 4 again could be formed by a plurality of thin sheets or strips placed the one above the 50 other. In each of those cases the desired result will be obtained with security, namely an unyielding connection of the middle ends of the main girders to the center-bearing and a free movability in vertical direction of the outer ends of the main 55 girders.

In the construction shown in Figure 3 the support 6, by means of the screws 7 is suspended to the cross-head 7^a, which latter, 60 by means of a ball-bearing, supports the turn-table, so as to roll on the center-bearing. The stand of the center-bearing is provided with a horizontal roller-abutment ring 8, against which bear two horizontal 65 rollers 2, fastened to the support 6. By the

arrangement of those rollers 9 bearing against the central abutment-ring 8, the middle of the turn-table is kept always securely to its place; and it is made impossible, that foreign bodies come between the 70 abutment-ring 8 and the rollers 9. This arrangement further will take up without any play and transfer to the center-bearing, all one-sided strains, which in consequence of 75 one-sided load on the turn-table arise in the direction vertically to the longitudinal axis of the turn-table.

The Figures 6 and 7 show, that below each main-girder 1 and 2 respectively there is arranged a pair of holders 11 respectively 80 12 for the roller-wheels. Those holders 11, 12 are connected to the main-girders 1, 2, by means of bolts 13, supported in a bearing beneath the main-girder, which connection allows a certain oscillating of the combination. The arrangement of the roller-wheels 14, 14^a, 15 on their holders 11, 12 is such, that on each side of each main-girder 1, 2 there is a roller-wheel, which rests on the rail 16 of the track of the turn-table. The 90 one pair of holders 11 is prolonged as indicated at 17, and on this prolongation there rests the means for driving the turn-table, which means may be an electric motor 18. A double toothed-wheel-gearing with 95 shafts 18^a, 19 and 20 transfers the rotation from the motor 18 to the tooth-gearing 21, which latter drives the roller-wheel 14^a. In order to avoid an undesired pressure on the roller-wheel 14^a, in consequence of the load 100 of the holders 17 and of the electric motor 18, there is arranged at the outer ends of those holders 17 an additional supporting wheel 22 which is held, with a certain tension, by the spring 23, so that the pressure 105 on the driving roller-wheel 14^a may never exceed the amount, which is needed for the driving of the turn-table, and that an excess of pressure on the rail, on the track and its foundation is avoided with security. The 110 pressure resulting from the load of the motor 18 and of the prolongation 17, which is transferred to the holders 11 and from there to the roller-wheel 14^a, can be regulated at will by choosing accordingly the 115 length of the prolongation, and by an adjustment of the supporting spring 23, so that always the desired adhesion and friction of the roller-wheel 14^a to the rail 16 is obtained, which is needed for the driving of 120 the turn-table.

I claim:

1. In a turn-table in combination main-girders, which are divided in the middle of their length above the center-bearing, a center-bearing, a support, arranged turnable on the center-bearing and flexible connecting-means, which are supported by and fastened to the support in a plane, which is perpendicular to the longitudinal axis of the turn- 130

table, and which means are fastened to the lower-sides of the central ends of the main-girders, in such a way, that outside of the theoretical line of contact between the support and the girder-ends the connecting-means will turn round the ends of the girders, whilst inside of the said theoretical line of contact the connecting-means will turn round the surface of the support.

5 10 2. In a turn-table in combination main-girders, which are divided in the middle of their length above the center-bearing, a center-bearing, a support arranged turnable on the center-bearing, flexible connecting-means, which lie at their middle-part on the support, and are fastened thereto and at their outer ends to the central ends of the main-girders, and horizontal rollers, arranged at the lower part of the turnable support and bearing against the aforesaid center-bearing.

15 25 3. In a turn-table in combination main-girders, which are divided in the middle of their length above the center-bearing, a center-bearing, a support, arranged turnable on the center-bearing, flexible connecting means, which are fastened at their middle part to the support, and at their outer ends to the central ends of the main-girders, a roller-abutment-ring, arranged horizontally round the lower part of the center-bearing, and horizontal rollers arranged at the lower part of the turnable support and bearing against the before-mentioned abutment-

30 35 4. In a turn-table in combination main-girders, which are divided in the middle of

their length above the center-bearing, a center-bearing, a support, arranged turnable on the center-bearing, flexible connecting-means, which lie at their middle part on the afore-said support and are fastened thereto and at their outer ends to the central ends of the main-girders, holders for the roller wheels, subdivided between the main-girders, the holder for the driven wheel being prolonged and carrying the driving means for the roller wheel.

5 10 15 20 25 30 35 40 45 50 55 60 65 5. In a turn-table in combination main-girders which are divided in the middle of their length above the center-bearing, a center-bearing, a support, arranged turnable on the center-bearing, flexible connecting-means, fastened with their outer ends to the central ends of the main-girders, and with their middle part in a plane transversely to the longitudinal axis of the turn-table on the afore-said support, horizontal rollers arranged at the turn-table in a plane transversally to the longitudinal axis of the turn-table, and bearing against the afore-said center-bearing, holders for the roller wheels, subdivided between the main-girders, the holder for the driven wheel being prolonged and carrying the driving means for the roller wheel.

In testimony whereof I have signed my name to this specification in the presence of two subscribing witnesses.

HANS SCHÜTTE.
